Patented July 9, 1918.

UNITED STATES PATENT OFFICE.

GARFIELD A. WOOD, OF DETROIT, MICHIGAN.

HOISTING AND DUMPING MECHANISM.

1,271,972.

Specification of Letters Patent. Patented July 9, 1918.

Application filed December 8, 1916. Serial No. 135,797.

To all whom it may concern:

Be it known that I, GARFIELD A. Wood, a citizen of the United States, and residing at Detroit, in the county of Wayne and 5 State of Michigan, have invented a new and Improved Hoisting and Dumping Mechanism, of which the following is a specification.

It is common practice to dump the contents of truck bodies by lifting the front end upwardly about pivots near the rear end of the chassis by means of hydraulic hoisting means. A convenient source from which to operate the hoisting means is the 10 propeller shaft; but, on account of the fact that the heavy loads and shocks incident to hoisting are borne on the side frames and independently of the propeller shaft, the deflection of the former is not transmitted 15 to the latter. Again, it is desirable to provide for slight inaccuracies in the construction of either hoists or chassis (often made by different manufacturers), whereby assembling of the parts is facilitated. It is 20 further desirable to avoid the liability of leakage which results from independently supporting the pumping and hoisting elements of which the hoisting means as a whole is made up. It is also desirable to 25 provide controlling means for the pump so arranged that if the control lever is jarred loose from normal or inoperative position, the weight of the parts is applied to the power receiving element in such manner as 30 to tend to hold the latter away from power receiving position. With these ends in view the present invention consists in a supplemental frame or support which extends across between the side bars of the 35 chassis at about the upper level thereof, said supplemental frame depending to and supporting at substantially the level of the propeller shaft a pump and mechanism, including a sprocket chain and clutch gear, 40 whereby the pump is driven. It also consists in the details of construction shown, 45 described and claimed.

Certain general combinations of elements and certain specific features relevant to the 50 construction of the mechanism shown and claimed herein are claimed in my earlier co-pending applications for United States Letters Patent, namely:—

S. N. 163,979, filed August 1, 1917 (re- 55 newal of S. N. 14,480, filed March 15, 1915)

and the division thereof, S. N. 115,957, filed August 21, 1916;

S. N. 14,479, filed March 15, 1915, and the division thereof, S. N. 117,235, filed 60 August 28, 1916.

The present invention is in the nature of an improvement on that indicated in my application for United States Letters Patent Serial Number 117,236, filed August 28, 1916.

In the drawings, Figure 1 is a fragmentary side view showing a preferred embodiment of the invention. Fig. 2 is a fragmentary view taken from the right side of Fig. 1. Fig. 3 is a fragmentary section on the line 3—3 of Fig. 2. Fig. 4 is a section 70 on the line 4—4 of Fig. 3.

1 indicates the side bars of the vehicle near the rear end of which are secured brackets 2 bearing pivots 3 about which the body 4 may be swung vertically for dumping purposes. The body may include the longitudinal frame pieces 5 so arranged as to rest, when in lowered position, either on the side bars or on special chairs (not shown) carried thereby. This general construction is well known.

Extending transversely across the side bars at a point just forward of the front end of the body and bolted or otherwise secured thereto are cross bars 8 (preferably 85 angle-irons having their horizontal flanges facing each other,) upon which rests the flanged base 9 of a hoisting cylinder 10, the piston rod 11 of which, through cross bar 12, sheaves 13, cables 14, equalizing bar 15, 90 shackle 16 and arms 17 secured to the body, serves to elevate the front end of the latter. The cylinder has secured to its upper end an expansion chamber or tank 19 that may be in free communication with the interior 95 of the cylinder above the piston (not shown), whereby storage space for liquid is formed.

In the embodiment shown, the front cross bar has secured thereto and depending therefrom at one side of the propeller shaft 100 21 (which extends longitudinally of the vehicle, being inclined somewhat downwardly and rearwardly, in the usual manner) an angle bar 22; and mounted on the face of the latter remote from the shaft is a gear 105 pump 23 of suitable construction, said pump being connected to the storage chamber in the cylinder and to the expansion chamber by a pipe 24, and also being connected to the lower end of the cylinder below the 110

piston by a delivery pipe 25. The flow of liquid through the pump is controlled by the valve arm 26, the operating link 28 of which leads to a hand lever 29 preferably mounted on the expansion chamber.

The drive shaft 30 of the pump is provided with a sprocket wheel 31 that is, in turn, driven by a sprocket chain 32 and gear 33, the hub portion 34, (Fig. 3) of which is rotatably mounted in a bearing 35 rigid with the member 22. Flanges 36 prevent longitudinal movement of the gear 33—34 through the bearing. The gear is perforated longitudinally and serves as a guide for clutch pins 36' which are carried by a longitudinally movable clutch member 33 that has a circumferential groove 39 in which are received pins 40 on the yoke arms 41. The latter are rigid with a pivot shaft 42, one end of which is carried in the lower end of the member 22, the other end being supported in an angle-bar 43 which depends from the bar 8 on the side of the propeller shaft opposite the member 22. An arm 44 rigid with the shaft 42 projects rearwardly therefrom and is pivotally connected to a link 45 that leads to a pivoted hand lever 46 preferably mounted on the expansion chamber 19—means, not shown, tends to retain the hand lever in the position indicated in Fig. 2 but it will be seen that in case it becomes loosened (as might occur in traveling over rough roads) the weight of the link is applied to the arm 44 in a manner such as to tend to hold the pins 36' withdrawn into the gear 33 or at the limit of their rearward movement, whereby they are prevented from accidentally engaging the clutch ring mentioned below. The pins 36', when thrown forwardly, project from the face of the sprocket gear 33 in position to engage teeth 48 on a floating clutch ring 49, the latter being grooved to receive pins 50 which extend radially inward from the divided member 51 that is held rigid with the shaft 21 by clamping bolts 52. Radial springs 53 may be interposed between the ring and the member 51.

It will be observed that the lower end of the transverse flange of the angle bar 22 is cut away to form a notch and that the pump is positioned therein. The pump is therefore located close to the bearing 35, being spaced therefrom only the thickness of the plate-like longitudinal flange of the angle bar. A very compact and stiff construction is thus secured without encroaching on the space usually required for other elements of the truck.

The openings in the clutch member 38, the gear 33—34 and ring 49, through which the propeller shaft passes are preferably of considerably larger cross sectional dimension than the shaft itself, consequently deflection of the supplemental frame 8, due to the

heavy loads carried thereby in hoisting, may take place without inducing transverse bending stresses in the propeller shaft. When the pins 36' are in engagement with the teeth of the clutch ring relative movement of the parts may take place which compensates for lack of alinement of the shaft and ring in one direction; lack of alinement in a direction at right angles thereto is compensated for by movement of the clutch ring longitudinally of the radial pins 50. The springs 53 prevent the clutch ring from shifting on the pins 50 when the clutch members are not engaged, and also prevent rattling.

By this construction it will be observed that the pump and clutch mechanism are so located that all relative deflection is avoided and that the chain 32 is very short; also that there is substantially no relative deflection between the pump cylinder and the pump, which avoids any undue tendency of the pipes 24 and 25 to become loosened at their points of connection.

The details of construction may obviously be varied considerably without departing from the spirit of the invention.

I claim:—

1. In combination with the side bars and a longitudinally extending shaft of a motor vehicle, a cross bar construction extending across between the side bars, said cross bar construction comprising a depending element including a thin plate arranged in a longitudinal plane of the vehicle, a pump mounted on said plate on the side thereof most remote from the shaft, and means for driving the pump from the shaft.

2. In combination with the side bars and a longitudinally extending shaft of a motor vehicle, a cross bar construction extending across between the side bars, said cross bar construction comprising a depending element including a thin plate arranged in a longitudinal plane of the vehicle, a pump mounted on said plate on the side thereof most remote from the shaft, and a clutch member mounted on the said plate on the side thereof nearest the shaft, means for driving the pump from the clutch member, and means for driving the clutch member from the shaft.

3. In combination with the side bars and the longitudinally extending propeller shaft of a motor vehicle, a supplemental support extending across between the side bars and depending to a point at substantially the level of the corresponding portion of the propeller shaft, a hoisting cylinder on the supplemental support, a driving member secured to the shaft, a pump and a pump driving gear supported on the depending portion of the supplemental support, said pump including a casing separate from the depending portion of the support, said shaft pass-

- ing through the gear, means for directing liquid from the pump to the cylinder and from the cylinder to the pump, and clutch means for connecting the pump driving gear 5 to the driving member at will, said means allowing deflection of the supplemental frame without inducing bending stresses in the shaft.
4. In combination with the side bars and 10 a longitudinally extending shaft of a motor vehicle, a pump support carried by the side bars, said support including an upright angle iron supported at its upper end, a pump and a clutch member both carried 15 solely by the lower end of the angle iron at about the level of the shaft, means for driving the pump from the clutch member, and means for driving the clutch member from the shaft.
5. In combination with the side bars and 20 a longitudinally extending shaft of a motor vehicle, a pump support carried by the side bars and including a substantially vertically arranged angle iron having one flange in a longitudinal plane of the vehicle, the lower portion of the other flange being removed 25 to form a notch, a pump mounted in the notch, and means for driving the pump from the shaft.
6. In combination with the side bars and 30 the longitudinally extending propeller shaft of a motor vehicle, a cross bar extending across between the side bars, a support rigid with the cross bar and depending therefrom 35 on one side of the propeller shaft, a pump carried by the support, a pump driving member also carried by said support, another support depending from the cross bar on the side of the propeller shaft opposite 40 the first mentioned support, means including a clutch for driving the pump driving member from the shaft, and clutch controlling means carried jointly by the two supports.
7. In combination with the side bars and 45 the longitudinally extending propeller shaft of a motor vehicle, a cross bar extending across between the side bars, supporting means rigid with the cross bar and depending therefrom on opposite sides of the propeller shaft, a pump and a pump driving member carried by said supporting means, 50 and clutch means, including a yoke pivoted to swing about a horizontal axis and mounted in the depending supporting means on 55 opposite sides of the propeller shaft, for driving said pump driving member from the shaft at will.
8. In combination with the side bars and 60 the longitudinally extending propeller shaft of a motor vehicle, a cross bar extending across between the side bars, supporting means rigid with the cross bar and depending therefrom on opposite sides of the propeller shaft, a pump and a pump driving 65 member carried by said supporting means, means for driving said pump driving member from the shaft at will, and means for controlling the last mentioned means so arranged that the weight of the parts tends 70 to hold said means out of pump driving relation.
9. In combination with the side bars and 75 the longitudinally extending propeller shaft of a motor vehicle, a cross-bar construction extending across between the side bars and depending therefrom, a clutch construction 80 encircling the shaft and comprising a member carried by the shaft and another member carried by the cross bar construction 85 considerably below the upper edges of the side bars, a pump supported by the cross bar construction and spaced considerably below the upper edges of the side bars, and means for driving the pump from the last mentioned clutch member.

GARFIELD A. WOOD.
